UNITED STATES PATENT OFFICE.

EWEN HENDERSON MITCHELL, OF BEDFORD, ENGLAND, ASSIGNOR OF ONE-THIRD TO
ALBERT EUSTACE SHORT AND ONE-THIRD TO HUGH OSWALD SHORT, BOTH OF
BEDFORD, ENGLAND.

AIRSHIP OF RIGID TYPE.

1,314,349.

Specification of Letters Patent. Patented Aug. 26, 1919.

Application filed April 23, 1919. Serial No. 292,073.

To all whom it may concern:

Be it known that I, EWEN HENDERSON MITCHELL, a subject of the King of Great Britain, residing at Bedford, Bedfordshire, England, have invented certain new and useful Improvements in Airships of Rigid Type, of which the following is a specification.

This invention relates to balloons or airships of rigid type, the object being to construct same in such form and manner that the structure is better adapted than heretofore to withstand the stresses due to the gas pressure, and consequently the structure can be made of the necessary strength while the weight can be decreased, advantages which will be obvious.

As at present constructed what is known as a rigid airship is generally circular or of slightly oval formation in transverse section, with the result that since the difference between the internal and external pressures varies from a very small pressure at the lowest point to a maximum pressure at the highest point, consequently the resulting tension in the fabric, circumferential wires or supporting rings, will vary, being greater at the top of the section and very small at the bottom and therefore bending moments and distorting stresses are introduced in the supporting structure which is usually partly counterbalanced by the tension of radial wires.

According to this invention the structure of the airship is made, in cross section, of a form such as hereafter described, so that in the average condition of pressure in the gas bags, the circumferential tension in the fabric, in the circumferential supporting wires and in the frames, will be constant, thus obviating the necessity for employment of most of the radial wires and reducing the pressure on the longitudinal members and the bending moments in the frames.

In describing the present invention it is first to be explained that a primary or elementary form of transverse section has been selected, necessary for constant tension when the pressure at the lowest point is equal to

atmospheric pressure, and such a form is shown in the outline diagram Figure 1 of the accompanying drawings, being such that the radius of curvature varies inversely as the pressure. This form shown at Fig. 1 is that which would be assumed by a cylindrical bag made of flexible material and open at the top, if filled with water, the bag having this form obviously being shown inverted in the diagram at Fig. 1.

Now the form shown at Fig. 1 would be unsuitable for the cross section of a rigid airship owing to the large ratio of height to breadth, and therefore according to this invention a plurality of forms similar to Fig. 1 are combined and the internal partitions which would result from such combination are removed.

The invention will be further described with reference to Figs. 2 and 3 of the accompanying drawings, Fig. 2 being a cross section of the airship sufficiently illustrating the same for the purposes of this specification, and Fig. 3 being a perspective view of a section of such an airship.

The gas container in transverse section is of a shape composed by portions of three of the forms shown at Fig. 1 conjoined, that is to say a laterally disposed portion 1 of the container conjoins at its upper part with a portion 2 of the upper part of such a form as is illustrated at Fig. 1, while the other laterally disposed portion 3 conjoins the opposite edge of the portion 2 and corresponds in shape to the portion 1, the sectional form of the gas container thus being composed of conjoined segments producing an approximately pear-shaped figure, hereafter referred to in this specification for the sake of brevity as "pear-shaped", the section so produced being such that the breadth and depth are sufficiently nearly equal and the volume sufficiently approximates to that of a circular section of the same height.

It will now be understood that the approximately pear-shaped transverse section referred to of the gas container has, externally at its upper part, two reentering angles which extend longitudinally and are

located at equal distances on opposite sides of the vertical central plane of the structure.

Such a gas container as described is constructed with closed ends as is well known, and several of such gas containers are located end to end within the outer framework of the airship. The outer framework consists of longitudinal frames 4 connected by transverse frames 5, and the construction of longitudinal and transverse frames need not be specially described in this specification since they may be composed of lattice structures built up of light sheet metal, and the lower ends of the transverse frames 5 abut and are fixed to a corridor 6 forming the keel of the vessel.

The frame work is stiffened by diagonal tension wires 7 shown only in one bay as at Fig. 2 so as not to complicate the drawing. The framework has a similarity to airships already constructed, excepting that at the upper part two of the longitudinal frames marked 8 and 9 are deeper to preserve the gas containers in the shape desired with the reentering angles as already described.

The external shape of the complete structure is maintained so as to obviate reentering angles and so as to reduce surface friction, by an outer cover 10, see particularly Fig. 2.

Circumferential wires 11, Fig. 3, are secured at their lower ends only to the corridor 6 where most of the weight is concentrated, the length of the wires 11 being such as to enable them to take up the shape shown, that is to lie in contact with the inner faces of the longitudinal frames 4, and the said wires 11 are retained in position at each longitudinal frame by any suitable means, but are free to move circumferentially, thus insuring that no side strain is transmitted to the frames, and that the tension is equal throughout.

The upper end of each of the lift wires 12, Fig. 2, is attached to one or other of the longitudinal girders 8, 9 of the framework, and the said wires 12 are taken through the gas bag at suitable points, say by conical neck pieces or other known devices, and their lower ends extend and are fixed to the lower part of the structure, that is to the corridor 6. The external shape of the structure is thus maintained in the longitudinal sense by the rigid framework, and the gas containers being of the form shown and described, the gas pressure produces practically no distorting stresses upon the rigid framework.

What I claim as my invention and desire to secure by Letters Patent is:—

1. A rigid airship comprising a gas container of approximately pear-shaped figure in transverse section, the radius of curvature being inversely proportional to the pressure, and in which the breadth and depth

are nearly equal, the upper part of said container having one or more reentering angles which extend longitudinally of the container and are located at equal distances on opposite sides of the vertical central plane of the said container, in combination with an outer rigid framework composed of longitudinal and transverse frame members conforming to the general contour of said gas container and having one or more of said longitudinal frames of sufficiently deep section to preserve the form of the said reentering angles of the said container.

2. A rigid airship comprising a gas container of approximately pear-shaped figure in transverse section, and in which the breadth and depth are nearly equal, the upper part of said container having one or more reentering angles which extend longitudinally of the container and are located at equal distances on opposite sides of the vertical central plane of the said container, in combination with an outer rigid framework composed of longitudinal and transverse frame members conforming to the general contour of said gas container and having one or more of said longitudinal frames of sufficiently deep section to preserve the form of the said reentering angles of the said container, an outer cover extending externally around the said framework to preserve the external shape of the complete structure while obviating reentering angles and internal lift wires connected at their upper ends to the deep section frames at the reentering angles and at their lower ends connected to the base of the structure, the said lift wires passing through the walls of the gas container.

3. A rigid airship comprising a plurality of gas containers each of approximately pear-shaped figure in transverse section having the breadth and depth nearly equal, the upper parts of said containers having one or more reentering angles which extend longitudinally of the containers and are located at equal distances on opposite sides of the vertical central plane of said containers, in combination with an outer rigid framework composed of longitudinal and transverse frame members conforming to the general contour of said gas containers in transverse section, one or more of said longitudinal frames of said framework being deeper than the other longitudinal frames to preserve the form of the reentering angles of said containers, a corridor forming the keel of the vessel to which the lower ends of said transverse frame members are fixed, circumferential wires secured at their lower ends only to said corridor, the length of said wires being such as to enable them to take up the form of the framework and containers in transverse section, said wires lying freely in contact with the inner faces of said longitudinal frames.

tudinal frame members in order to support
said gas containers in the spaces between
said transverse frame members, lift wires
extending interiorly from the upper part of
5 the structure to the lower part thereof, and
an outer cover extending exteriorly over the
rigid framework.

In witness whereof I have hereunto set my
hand in the presence of two witnesses.

EWEN HENDERSON MITCHELL.
